UNITED STATES PATENT OFFICE.

SANFORD A. MOSS, OF LYNN, MASSACHUSETTS, ASSIGNOR TO GENERAL ELECTRIC COMPANY, A CORPORATION OF NEW YORK.

SUPERCHARGER FOR INTERNAL-COMBUSTION ENGINES.

1,413,420.

Specification of Letters Patent. Patented Apr. 18, 1922.

Application filed December 17, 1920. Serial No. 431,346.

To all whom it may concern:

Be it known that I, SANFORD A. Moss, a citizen of the United States, residing at Lynn, in the county of Essex, State of Massachusetts, have invented certain new and useful Improvements in Superchargers for Internal-Combustion Engines, of which the following is a specification.

The present invention relates to superchargers for internal combustion engines and particularly to superchargers which comprise a turbo-compressor driven by exhaust gases from the engine. As is now known, such superchargers are employed for supplying air to the engine at substantially uniform pressure irrespective of the surrounding atmospheric pressure, the discharge side of the supercharger compressor being connected to the engine carburetor or carburetors.

The object of my invention is to provide an improved structure and arrangement in an apparatus of this character and for a consideration of what I believe to be novel and my invention, attention is directed to the accompanying description and the claims appended thereto.

My improved structure and arrangement is particularly adapted for use in connection with aeroplanes and in the drawing I have illustrated such application but it will be understood that the invention is not necessarily limited to this particular use.

In the drawing, Fig. 1 is a side elevation of an aeroplane internal combustion engine equipped with supercharger apparatus embodying my invention; Fig. 2 is a top plan view thereof; Fig. 3 is a face view, the propeller being partly broken away; Fig. 4 is a side elevation partly in section of a part of the structure, the figure being on a larger scale than Fig. 1, and Fig. 5 is a face view of the parts shown in Fig. 4 with the compressor casing and turbine wheel removed.

Referring to the drawing, 8 indicates the crank casing of an internal combustion engine, 9 the cylinders, and 10 the crank shaft. In the present instance, a twelve cylinder engine is illustrated there being two rows of six cylinders each arranged in V-shaped relation to each other. The intake manifolds 11 of the engine cylinders are located between the two rows of cylinders and are connected to carburetors 12, and the exhaust pipes 13 of the cylinders are connected to conduits 14, one on each side of the engine.

At their forward ends conduits 14 are connected by flanged joints 15 to a nozzle box 16 and at their rear ends they are provided with suitable valves 17 which are connected by rods 18 to a suitable operating lever whereby the valves may be opened and closed at will. In nozzle box 16 are one or more nozzles 19 (Figs. 4-5) for directing exhaust gases against the buckets of a turbine wheel 20. Turbine wheel 20 has no casing, the gases exhausting from it directly to atmosphere, and it is carried by a shaft 21 supported in a rear bearing 22 and a forward bearing 22^a. The compressor casing 23 is indicated at 23 and in it is an impeller, not shown, which receives air on opposite sides at its central portion and delivers it at its periphery to a discharge conduit 24. Air is supplied to the forward side of the impeller through an opening 25 in casing 23 and to the rear side of the impeller through a conduit 26 which leads from the front of the casing around to the rear of it. Shaft bearing 22^a is located in inlet 25 and is supported by casing 23. It is preferably in the form of a combined supporting and thrust bearing which fixes the shaft against axial movement. A conduit 27 leads from the front of the casing 23 to the rear for discharging cooling air to a vertically extending conduit 27^a which forms a housing and support for bearing 22, the air serving to cool the bearings. On crank shaft 10 is an aeroplane propeller 28 and it will be noted that opening 25 and conduits 26 and 27 face toward the propeller so as to receive air from it. At 27^b is a baffle which takes air from the propeller and delivers it to the front side of the turbine wheel for cooling it.

In operation when valves 17 are open the exhaust from the engine passes directly to atmosphere and no pressure is built up in nozzle box 16. When it is desired to supercharge, valves 17 are closed more or less thereby causing exhaust gases to flow to nozzle box 16 and build up a pressure therein, gases then escaping through the nozzle or nozzles 19 against the buckets on turbine wheel 20. This drives the turbo-compressor, the impeller of the compressor delivering air to discharge conduit 24. The speed of the turbo-compressor and hence the pressure of the air discharged can be controlled by adjusting valves 17 as is now understood. The gases exhaust from the engine at a

high temperature which means that the nozzle box, turbine wheel and parts associated therewith become very hot during operation, thereby causing considerable expansion and 5 contraction of the parts, also the air discharged from the compressor may be quite hot due to being compressed. My present invention relates more particularly to the 10 structure and arrangement for mounting the supercharger on the engine so it may expand and contract without getting out of alignment or becoming distorted and providing for the cooling of the supercharged air after it leaves the compressor and before 15 it is delivered to the engine.

According to my invention, the supercharger comprising the turbo-compressor, nozzle box, rear bearing and forward bearing are built as a unitary, rigid structure and 20 this structure is then carried by a bracket supported on the engine, the bracket being adapted to permit the rigid supercharger structure to move axially as a whole. The carburetors are arranged above the engine 25 cylinders and are connected to the discharge side of the compressor by a number of pipes which have a certain amount of flexibility to permit limited axial movement of the supercharger structure. These pipes also serve 30 as a cooler for the supercharged air being arranged in the aeroplane propeller air stream so that air discharged from the aeroplane propeller passes over them. I also so arrange the structure that the compressor 35 and turbine wheel may be removed from the engine without disturbing the nozzle box or its connections with exhaust conduits 14. This is an important consideration as the joints 15 have to be made to stay tight under 40 most severe operating conditions and hence it is very desirable not to disturb them after they have been sealed up.

Referring to the particular embodiment of 45 my invention illustrated in the drawing, the supporting bracket comprises two spaced vertical arms 30 connected adjacent their lower ends by a transverse rib 31. The lower ends of arms 30 have inturned portions 32 which rest on and are bolted to the 50 nose of the engine as indicated at 33. The upper ends of arms 30 are provided with bosses 34 which are bolted by bolts 34^a directly to lugs 35 which depend from the nozzle box. At its top the nozzle box is connected 55 to the compressor casing by a flat plate 36, the plate being preferably formed integral with or welded to the nozzle box and detachably connected to the compressor casing as by a bolt or bolts 37. At its two 60 sides the nozzle box is also supported by exhaust conduits 14 to which it is bolted at the flanged connections 15. The rear bearing 22 is supported by suitable webs 38 in the enlarged upper portion of conduit 27^a. 65 The forwardly facing opening of conduit

27^a joins conduit 27 in the vertical plane marked B in Fig. 4. The outline of this opening is shown in Fig. 5 at C. At the two sides of conduit 27^a are marginal flanges 39 which are bolted directly to pads 40 on the 70 rear of the compressor casing by bolts 41. Flanges 39 are fastened to brackets 30 by bolts 42. By this arrangement the rear bearing is directly fastened to and forms a rigid 75 structure with the compressor casing and both the compressor casing and bearing are carried by the supporting bracket which comprises arms 31. The carburetors 12 are provided with an air supply header 44 and this header is connected to discharge conduit 80 24 of compressor 23 by a number of curved tubes 45.

It will thus be seen that the supercharger as a whole can move slightly axially, the supporting bracket and tubes 45 being sufficiently flexible to permit of this, and since it moves as a unit the bearing alignment will not be disturbed. Such movement may be caused for example, by the expansion and 90 contraction of exhaust conduits 14. 90

As will be clear, the arrangement is such that the nozzle box or any of the other parts containing hot gases can warp or distort without changing the line-up of the turbine wheel in its bearings. The bearings are all 95 mounted on a structure which remains more or less cool and which forms a single unit independent of the nozzle box structure. It will be noted that the nozzle plate in which 100 nozzles 19 are formed is supported by bracket arms 30 so such nozzles are supported by the same flexible support which also supports the structure carrying the compressor casing, both shaft bearings being 105 likewise attached directly to this structure. The structure carrying the compressor casing 110 is comparatively cool, hence no matter how much the parts subjected to red hot gases expand and warp, the turbine wheel will always remain closely adjacent the nozzle plate through which the hot gases pass to the turbine wheel.

Since bearing 22^a is in the form of a thrust bearing, when expansion takes place there will be no relative movement between the 115 impeller wheel and its casing and hence there is no tendency for the impeller to take a position where it might strike the casing. If there is relative expansion between the structure carried by the flexible supporting 120 bracket and the shaft, it will cause the clearance between the turbine wheel and the nozzle plate to vary. However, the shaft and casing structure are comparatively cool so this differential expansion is negligible compared with the clearance between the turbine wheel and the nozzle plate. As a result striking or rubbing of either the turbine wheel or compressor impeller with adjacent 125 stationary parts is avoided. 130

If it is desired to remove the turbo-compressor for replacement, repair or other reasons, bolts 37 and 42 are removed when the unit comprising compressor, turbine wheel and rear bearing can be lifted from

5 the engine as a whole. This does not disturb the nozzle box or its connections with conduits 14, and avoids the breaking of the sealed connections 15.

10 If it is desired to remove the compressor casing without disturbing the rear bearing then instead of removing bolts 42, bolts 41 may be removed. This permits the compressor casing and turbine wheel to be removed 15 but leaves the rear bearing bolted to bracket arms 30.

15 The air delivered by compressor 23 passes through tubes 45 to carburetor header 44 and while passing through the tubes is cooled by the outside air passing over the outer surface of the tubes. Since tubes 45 lie directly in the air stream of the propeller 28 a large volume of air passes over and around them thereby most efficiently cooling the supercharged air.

20 In accordance with the provisions of the Patent Statutes, I have described the principle of operation of my invention, together with the apparatus which I now consider 30 to represent the best embodiment thereof, but I desire to have it understood that the apparatus shown is only illustrative and that the invention may be carried out by other means.

25 What I claim as new and desire to secure by Letters Patent of the United States, is:—

1. In combination, an internal combustion engine, a supercharger, a conduit connected to the supercharger and to the engine 40 which is subjected to temperature changes which cause it to expand and contract, and means for yieldingly supporting the supercharger on the engine.

2. In combination, an internal combustion engine having an exhaust conduit, a supercharger having a nozzle box fastened to said conduit, and yielding means for supporting the supercharger.

3. In combination, an internal combustion engine having an exhaust conduit, a supercharger having a nozzle box fastened to said conduit, and an axially yieldable bracket for supporting the supercharger.

4. In combination, an internal combustion engine having an exhaust conduit, a supercharger comprising a compressor casing and a nozzle box, said nozzle box being fastened to the exhaust conduit, and a yieldable bracket for supporting the supercharger, 60 said nozzle box and compressor casing being fastened to the bracket by separate means.

5. In combination, an internal combustion engine having an exhaust conduit, a supercharger comprising a turbo-compressor and a nozzle box, the latter being fas-

tened to said exhaust conduit, yielding means for supporting the supercharger on the engine, and yielding conduit means connecting the discharge side of the compressor to the engine.

6. In combination, an internal combustion engine having an exhaust conduit, a supercharger comprising a turbo-compressor and a nozzle box, the latter being fastened to said exhaust conduit, an axially yieldable bracket for supporting the supercharger, and conduit means connecting the discharge side of the compressor to the engine.

7. The combination with an aeroplane engine having a propeller on its crank shaft, and an exhaust conduit, of a supercharger comprising a turbo-compressor and a nozzle box, the latter being fastened to said exhaust conduit, yielding means for supporting the supercharger on the engine, and yielding conduit means located in the air stream of the propeller and connecting the discharge side of the compressor to the engine.

8. The combination with an aeroplane engine having a propeller on its crank shaft, of a supercharger for the engine, means for supporting the supercharger, and conduit means comprising a plurality of pipes for conveying supercharged air from the supercharger to the engine, said conduit means being located in the air stream of the propeller.

9. The combination with an aeroplane engine having a propeller on its crank shaft, of a supercharger for the engine, means for supporting the supercharger, and a plurality of pipes located in the air stream of the propeller for conveying supercharged air from the supercharger to the engine.

10. The combination with an aeroplane engine having a propeller on its crank shaft and an exhaust conduit, and a supercharger comprising a turbo-compressor adapted to be operated by exhaust gases from the engine and a nozzle box connected to said exhaust conduit, of an axially yieldable supporting bracket, and means connecting the turbo-compressor and nozzle box to said bracket.

11. The combination with an aeroplane engine having a propeller on its crank shaft and an exhaust conduit, a supercharger comprising a turbo-compressor adapted to be operated by exhaust gases from the engine and a nozzle box connected to said exhaust conduit, of an axially yieldable supporting bracket, separate means connecting the compressor casing and the nozzle box to said bracket, and detachable means connecting the nozzle box to the compressor casing.

12. The combination with an aeroplane engine having a propeller on its crank shaft and an exhaust conduit, a supercharger com-

prising a turbo-compressor adapted to be operated by exhaust gases from the engine and a nozzle box connected to said exhaust conduit, of an axially yieldable supporting bracket, separate means connecting the compressor casing and the nozzle box to said bracket, detachable means connecting the nozzle box to the compressor casing and

yieldable conduit means located in the propeller air stream connecting the discharge 10 side of the compressor to the engine.

In witness whereof, I have hereunto set my hand this thirteenth day of December, 1920.

SANFORD A. MOSS.
